UNITED STATES PATENT OFFICE

143,085

DESIGN FOR A BREATHING APPARATUS

John B. Littlefield, Mahanoy City, John H. Schneider, Irwin, and William P. Yant, Murraysville, Pa., assignors to Mine Safety Appliances Company, Pittsburgh, Pa.

Application January 16, 1942, Serial No. 105,237

Term of patent 14 years

(Cl. D83—1)

To all whom it may concern:

Be it known that we, John B. Littlefield, John H. Schneider, and William P. Yant, citizens of the United States, residing respectively at Mahoney City, in the county of Schuylkill and State of Pennsylvania; Irwin, in the county of Westmoreland and State of Pennsylvania; and Murraysville, in the county of Westmoreland and State of Pennsylvania, have invented a new, original, and ornamental Design for Breathing Apparatus, of which the following is a specification, reference being had to the accompanying drawings, forming a part thereof.

Fig. 1 is a side elevational view of a breathing apparatus embodying our new design;

Fig. 2 is a front elevational view thereof; Fig. 3 is a rear elevational view thereof; and Fig. 4 is an elevational view of the side opposite that shown in Fig. 1.

The dominant features of our design reside in the portions shown in full lines.

We claim:

The ornamental design for a breathing apparatus, substantially as shown and described.

JOHN B. LITTLEFIELD.
JOHN H. SCHNEIDER.
WILLIAM P. YANT.
